GUIDE FOR MAKING LACE AND THE LIKE

Albert B. Collingbourne, Elgin, Ill.

Application March 30, 1935, Serial No. 13,809

2 Claims. (Cl. 112—9)

This invention relates to a guide for making lace and more particularly to an adjustable guide which may be used for lace making and for holding yarn while it is being stitched by a sewing machine to a foundation pattern.

The device is exceedingly simple and inexpensive, adjustable as to width, and provided with means for maintaining a uniform width from end to end of the guide.

10 In the drawing:

Fig. 1 is a plan view of a guide for making lace and the like, embodying my invention.

Fig. 2 is a side view of the same.

Fig. 3 is a transverse section taken on the line 15 3—3 of Fig. 1.

In that embodiment of my invention shown in the drawing, flat, relatively thin side bars are indicated at 10 and 11, respectively. These may be made of metal or other suitable material.

20 Each of said bars is preferably bent near one end, as indicated at 12 in Fig. 2.

An end piece 13 is provided for engaging the ends of the side bars 10 and 11, and a similar end piece 14 for the opposite ends of the two bars.

25 Each of the end pieces 13 and 14 is made of a flat piece of metal bent between its ends at 15 and 16 (Fig. 3) to form ends 17 parallel with and slightly spaced from the part 18 of each end piece. The portion 18 is provided with indentations 19 arranged in two rows, the indentations of one row being aligned with those of the other, and each pair of aligned indentations being spaced from an adjacent pair and from the side walls of the end pieces a distance sufficient to ac-

30 commodate the side bars in any of the spaces indicated at 20 in Fig. 3 or in the locations they occupy in the drawing. The dotted lines in Fig. 1 indicate how the side bars may be moved to adjust the width of the guide.

35 40 The end pieces 13 and 14 are removable for the

purpose of adjusting the positions of the side bars and also for the purpose of slipping the finished lace off the side bars at one end of the device.

The bend 12 in the bars 10 and 11 results in the end piece 14 being located at an angle to the body of the device and enables the user conveniently to hold and move the guide when it is resting on a foundation pattern on a sewing machine for stitching the yarn on the guide to the pattern. 5

Changes may be made in details of construction without departing from the scope of my invention and I do not intend to be limited to the exact form shown and described, except as set forth in the appended claims. 10 15

I claim:—

1. A guide for making hairpin lace and the like comprising a pair of separate side bars about which loops of thread are slidably arranged, and two separate end pieces detachably engaging the 20 ends of the side bars, each end piece consisting of a strip bent upon itself and forming parallel arms, and having projections on the strip dividing the space between the arms into a plurality of spaces, the ends of the side bars being frictionally 25 engaged in adjusted positions between said arms and projections.

2. A guide for making hairpin lace and the like comprising a pair of separate side bars about which loops of thread are slidably arranged, and 30 two separate end pieces detachably engaging the ends of the side bars, each end piece consisting of a strip bent upon itself and forming parallel arms, and having projections on the strip dividing the space between the arms into a plurality of spaces, 35 the ends of the side bars being frictionally engaged in adjusted positions between said arms and projections, the side bars being bent near one end adjacent the inner edge of one end piece.

ALBERT B. COLLINGBOURNE. 40
